UNITED STATES PATENT OFFICE

118,294

DESIGN FOR A MERCHANTISE DISPLAY STAND UNIT

José Trojan, Chicago, Ill., assignor to Owen Housholder and David C. Cohen, copartners, doing business as Crystal Manufacturing Co., Chicago, Ill., a corporation of Illinois

Application October 23, 1939, Serial No. 87,819

Term of patent 3½ years

To all whom it may concern:

Be it known that I, José Trojan, a citizen of the United States, residing at Chicago, in the county of Cook and State of Illinois, have invented a new, original, and ornamental Design for a Merchandise Display Stand Unit, of which the following is a specification, reference being had to the accompanying drawing, forming part thereof.

I claim:

The ornamental design for a merchandise display stand unit, substantially as shown.

JOSÉ TROJAN.
